FOUNDRY MOLD WITH SECTIONAL MATCH PLATES OF DIFFERENT SIZES

Erwin Bührer, Schaffhausen, Switzerland

Application January 20, 1955, Serial No. 483,137

Claims priority, application Switzerland June 12, 1954

3 Claims. (Cl. 22—157)

The invention relates to means for producing molds for foundry purposes.

It is an object of the present invention to provide means facilitating the preparation of molds from a plurality of pattern plates within the confines of a single pattern molding flask regardless of the materials of which the pattern plates are fabricated.

It is another object of the present invention to provide means conducive to an efficient mold box structure which permits the preparation of molds from numerous match plates in a single operation and which further permits variation in the number, as well as of the sizes of the match pattern plates for each molding operation, said match pattern plates being made of different materials, if desired.

Still another object of the present invention is to provide means capable of greatly simplifying the simultaneous preparation of molds from numerous match pattern plates and thus substantially increasing the attainable rate of preparation of said molds.

A further object of the present invention is to provide means leading to highly improved and extremely efficient multi-element mold preparing devices which are easily manipulatable during dismantling to permit changes in the number of match plates to be employed as well as during reassembly subsequent to the making of such changes.

It is still a further object of the present invention to provide means affording sturdy, yet readily releasable, resilient connections between the molding flask and the match plate supporting means of a mold preparing device, whereby rearrangement of the pattern plates of said device can be carried out with minimum expenditures of time and energy.

Yet another object of the present invention is to provide means presenting novel and simplified mold preparing devices wherein the pattern or patterns on the match plates are rigidly supported and precisely located during formation of the molds but may be vibrated thereafter to facilitate removal of finished molds from said pattern plates.

It is still another object of the present invention to provide means forming mold preparing devices which are inexpensively and rapidly manufactured and which eliminate any need for a multiplicity of machines to prepare molds from a plurality of individual patterns on match plates of different characteristics.

Various constructions of mold preparing devices have heretofore been proposed with the avowed aim of permitting formation of molds from a plurality of match plates simultaneously. All of these have, however, suffered from a number of disadvantages. Among these are that the match plates employed cannot be removed or replaced by other plates without large expenditures of time and effort, and that the match plates bearing the pattern or patterns cannot be located with sufficient accuracy and precision except by use of unduly cumbersome and expensive structural elements.

2

The primary purpose of the present invention, consequently, is to overcome the above mentioned disadvantages as well as to eliminate any deficiencies inherent in prior known devices for preparing molds and not specifically enumerated above.

These and other objects of the invention will become further apparent from the following detailed description, reference being made to the accompanying drawings, showing preferred embodiments of the invention.

In the drawings:

Fig. 1 is a vertical sectional view of a mold preparing device embodying the invention taken along line I—I in Fig. 2;

Fig. 2 is a top plan view of said device;

Fig. 3 is a partial sectional view of the device taken along line III—III in Fig. 2, the vibrator being omitted;

Fig. 4 is a partial sectional view of the device taken along line IV—IV in Fig. 2;

Fig. 5 is a partial sectional view of the device taken along line V—V in Fig. 2;

Fig. 6 is a partial sectional view of the device taken along line VI—VI in Fig. 2, the vibrator being omitted;

Fig. 7 is a partial sectional view of the device taken along the line VII—VII in Fig. 2 and illustrating the vibrator;

Figs. 8, 9 and 10 schematically illustrate various ways in which the pattern plate arrangement of the device may be varied;

Fig. 11 is a partially sectional front view of means for attaching a connecting frame as used with the invention to the pattern table;

Fig. 12 is a sectional view taken along the line XII—XII of Fig. 11;

Fig. 13 is a sectional view of a modification of attaching means between the frame and the pattern table;

Figure 14 is a sectional view of a further modification of attaching means between the frame and the pattern table taken along the line XIV—XIV of Fig. 15; and

Fig. 15 is a sectional view of the structure of Fig. 14 taken along the line XV—XV in Fig. 14.

Referring now more particularly to Figs. 1 and 2, there is shown support means or table 1 for a match plate on which table is located an intermediate support 2 carrying a match plate 3 with models or patterns 4 and 5 surrounded by rim portions. A further intermediate support 6, in which a suitable heating device 7 is mounted, and on which a match plate 8 provided with a pattern 9 surrounded by rim portions is located, is also carried by table 1. Match plates 10 and 11 are associated with table 1 in a similar manner. In somewhat modified fashion, a plaster plate 12 which supports a model 13 is mounted on a special intermediate member or base plate 14 which in turn is attached to part 15 of table 1. Plaster plate 12 may, of course, be retained directly by table 1, part 15 without the use of base plate 14.

Two bolts 34, which are mounted in table 1, serve to center and accurately locate support 2 as well as the two bolts 35 in the support 2 and pattern plate 3. In a similar manner, bolts 36, 37 and 38 cooperate with support 6 and match plate 8. The intermediate means constituted by the various plate-supports are thus removably secured to the mold table 1.

A closed frame 16 has attached thereto ledges 17 by means of bolts or screws 18. Frame 16 and ledges 17 are secured against relative displacement by means of pins 19. Frame 16 is mounted by means of ledges 17 directly on the pattern carrying match plates 3, 8, 10, 11, and 12, said ledges partially overlying the rim portions of said match plates. Secured in frame 16 by means of nut 21 is a round dowel pin 20, and a further dowel pin 22 provided with flat surfaces is secured in frame 16 by means of nut 23.

Frame 16 is attached to table 1, or alternatively to base support of plate 14, by means of a plurality of threaded bolts 24 and nuts 25 spaced around the periphery of the frame. In case base support 14 is used the latter must, of course, be rigidly attached by means of screw bolts 26 or like fasteners to table 1. Supported on ledges 17 and thereby on frame 16 is a molding flask 27, the dowel openings of which in conjunction with dowel pins 20 and 22 fix the location of the molding flask.

As may be seen in Figs. 1, 2, and 3, a ledge 28 is provided which is fixed in and transversely of frame 16 by means of bevel shoulders 29 and screws 30. In like manner, a ledge 31 (Fig. 2) is fixedly mounted between frame 16 and ledge 28. A further ledge 32 (see Figs 1, 2, and 4) is loosely mounted on match plates 3 and 8 and is held in place by the bevel shoulders on ledges 17 and 31. Likewise, ledge 33 is loosely supported between match plates 10 and 11 and held in place by means of ledges 17 and 31. The above enumerated clamping ledges effectively divide frame 16 into a plurality of compartments or sections corresponding in number to the number of match plates employed.

The construction of frame 16 and ledges 17 is shown in somewhat greater detail in Fig. 5. It may be seen that ledges 17 have a surface 40 in contact with a corresponding surface on pattern plate 41, while frame 16 and match plate support 42 are spaced from one another. The respective surfaces 43 should be accurately constructed within the factory-specified tolerance limits to ensure that surface 40, when it rests on the cooperating surface of plate 41, is in complete contact with the latter surface. As may be seen in Fig. 5, surfaces 43 fix the horizontal location of plate 41 relative to ledge 17 and dowel pin 49, while bolt 44 has a certain amount of play in all directions in pattern plate 41.

In order to eliminate the need for manufacturing surfaces 43 on ledge 17 as well as on plate 41 with a great degree of precision, which is ordinarily very difficult to attain, the construction may be as shown in Fig. 6. In this modification, match plate 45 is provided with a rectangular abutment surface 46 corresponding to a rectangular abutment surface 47 on ledges 17 to fix the horizontal location of the plate relative to dowel pin 48. In order to facilitate mounting of frame 16 and ledges 17 on any match plate, abutment or guide surface 47 on ledges 17 is partially inclined to the horizontal, as shown at 50. As may be seen in Fig. 1, the upper surface of ledges 17 may coincide with the upper surfaces of the various match plates 3, 8, 12, 10, 11, and of ledges 28 and 31 as well as of detachable ledges 32 and 33. In Figs. 5 and 6 the upper surface of ledges 17 is somewhat higher than the upper surfaces of the match plates 41 and 45 and the other parts of the apparatus.

Mounted on frame 16 are two vibrators 51 and 52 (Fig. 2) of substantially similar construction. As may be seen in Fig. 7, each vibrator includes a reciprocable piston 53 provided with spaced annular grooves, a spring 54, an air inlet conduit 55, a closure plate 56, the spring being mounted between said plate and the piston, and suitable air exit openings in the body of the vibrator. Inasmuch as these vibrators are conventional, their operation will not be further described. The function of these vibrators, as will be more fully explained below, is to facilitate removal of finished molds from the device.

Referring now to Figs. 8, 9, and 10, it may be seen how the mold preparing device of the present invention may be modified for any number of match plates. Thus, in Fig. 8 there are schematically shown two match plates 57 and 58 between which a crosspiece 59 is loosely mounted and fixedly supported by a frame 60. In Fig. 9, three match plates 61, 62, and 63 are illustrated with a loosely inserted ledge 64 located between plates 62 and 63 and held by means of frame 65 and a fixed ledge 66 mounted in said frame. Fig. 10 shows schematically six match

plates 67 to 72 and loose ledges 73, 74, and 75 which rest on respective match plates and are fixedly held by means of a frame 76 and ledges 77 and 78 rigidly mounted in the frame. From Figs. 8 to 10 it may be readily inferred that the device of the present invention may be adapted to operation with any desired number of pattern carrying match plates merely by varying the number and distribution of the ledges to thereby vary the number of match plate compartments or sections formed within the frame.

In lieu of means 24, 25 for holding frame 16 to pattern table 1, the modified constructions illustrated in Figs. 11 to 15 may be employed. Referring first more particularly to Figs. 11 and 12, there is illustrated a resilient or elastic clamp 79 having one end portion inserted in a bushing 80 housed in table 1 and another end portion hooked onto a projection 81 of frame 16, whereby frame 16 is continually biased toward table 1 by virtue of the tension of the clamp. Such means for retaining frame 16 on table 1, or alternatively on base plate 14, has been found to be extremely efficient in use.

In Figs. 11 and 12 there is further illustrated in dotted lines a key or operating member 82 having a cam end 83 inserted in clamp 79. Key 82 can be rotated in clamp 79 in the direction of arrow 84 so as to distend the clamp and permit its removal from bushing 80 and projection 81. The number of clamps 79 which are employed to connect frame 16 to table 1 (or base support 14) will depend on the size of the frame 16.

A further modification of this structure is illustrated in Fig. 13. Frame 16, provided with an abutment ledge 85, is connected to table 1 through lever 86 connected by means of pin 88 to one leg of a bell-crank lever 87, the latter being rotatably mounted on pin 89 and having its other end pivotally connected to piston rod 90 by means of pin 91. Springs 92 and 93 pressing against piston 94 hold the frame 16 through the intermediary of the aforementioned parts to molding table 1. In order to release this elastic connection, compressed air may be admitted to cylinder 96 by means of conduit 95 so as to move piston 94 in such a manner as to compress springs 92 and 93. By providing a common air inlet in table 1 it is then possible to release all of the various frame clamping devices simultaneously.

Still a further modification of the clamping device is illustrated in Figs. 14 and 15. Each clamping device includes a piston 97 which is connected by means of a yoke 98 to a clamping element 99 suspended from the yoke by means of a pin or bolt 100. Clamping element 99 is provided with an eye portion 101 which fits over a bolt 102 on table 1. Piston 97 is normally urged upwards by Belleville washers or other suitable spring elements 103 so as to maintain eye portion 101 in contact with bolt 102 to thereby clamp frame 16 to table 1.

If screw 104 is rotated in one direction, then piston 105 will be moved to the right in Fig. 14 against the grease filling 106 to press the same through channels or conduits 107, 108 and 109 etc. into the respective cylinders 110. In this manner, the various pistons 97 are pressed downwardly against the force of spring washers 103. Clamping elements 99 are thereby loosened from bolts 102 and projections 111 come in contact with stops 112 connected to frame 16. Consequently, each element 99, i.e., eye portion 101, is pivoted into the position 113 illustrated in dotted lines in Fig. 15, while at the same time each pin 114 is pressed by projection 111 into the bore in which it is housed and against the force of spring 115. In this manner frame 16 is released and may be removed.

If screw 104 is now turned in the opposite direction, then spring washers 103 press piston 97 upwardly and thereby expel the grease from cylinders 110. Yokes 98 are moved upwardly and the force of springs 115 acting through pins 114 on projections 111 pivot eye portions 101 back into their normal positions, an example of which is illustrated in Figs. 14 and 15. Eye portions 101 are

thus once more in contact with bolts 102 and spring washers 103 again resiliently clamp frame 16 to table 1.

It is, of course, possible to actuate piston 105 by means of compressed air or other pressure fluid rather than by screw 104 so as to operate this clamping device. In such a case, manual operation of the devices is eliminated. Should frame 16 be extremely heavy it is advantageous to provide an arrangement by means of which frame 16, when released from table 1, may be vertically raised and then swung away therefrom while match plates are exchanged, after which frame 16 may be returned to its operative position by this arrangement.

In the embodiment of the invention illustrated in Fig. 1, for example, match plate 3 is made of wood and is provided with wooden patterns 4 and 5, pattern plates 8, 10, and 11 are made of metal and are provided with metallic patterns or models 9, 116 and 117 (Fig. 2) threadedly attached thereto and having located therebeneath heating devices 7, and match plate 12 is a plaster filled box with a model 13 cemented therein. It is, therefore, evident that the present invention permits combination of match plates carrying patterns of different sizes, shapes, and materials into a unitary mold forming device. By virtue of the fact that dowel pins 20 and 22 are mounted directly in frame 16, location of the various match plates in a horizontal plane with a high and constant degree of accuracy and precision is made possible. Since the thicknesses of the various match plates and the heights of the various plate supports may be accurately manufactured, also the elevation of the individual match plates above the mold table can be guaranteed.

It is possible by locating the upper surfaces of the match plates slightly lower than the upper surfaces of ledges 17 to obtain a mold half with a face protruding somewhat beyond the edge of the molding flask, which fact contributes to a more intimate joint between said mold half and a complementary mold half having a recessed surface substantially in the plane of separation upon assembly of said portions into a complete mold. By virtue of the fact that vibrators 51 and 52 are mounted directly in frame 16 and work in mutually perpendicular directions, a multilateral shaking of the various match plates in the parting line is attainable which facilitates removal of the mold from the match plate.

Bolts 34 to 39 and 44 (see Fig. 5 for the latter) loosely center the supports or intermediate members 2 and 6, the heating device 7 and the various match plates, and these may, therefore, be removed and exchanged easily and without effort when frame 16 is removed. Because of the conical guide surfaces 43 or 50 formed on frame 16 and ledges 17, the match plates may be precisely located and fixed in position with a minimum of effort. The insertion of fixed, rigid ledges or crosspieces such as 28, 31, 66, 77 and 78 to aid in forming the requisite number of compartments in the frame for the pattern carrying match plates further increases the preciseness of location of the match plates employed and additionally braces frame 16. Supplementary use of loose ledges or crosspieces then permits unlimited subdivision of the apparatus. It will be seen to be more advantageous, when a change in format becomes necessary, not to remove the various fixed ledges but only to employ as many loose ledges as are required by the different numbers of patterns involved.

The apparatus of the present invention further enables the operator to fill small orders for limited numbers of items, which for economic reasons can be manufactured only with wooden or plaster match plates, in conjunction and simultaneously with other orders requiring use of high precision, metallic match plates and patterns or models. Above all, it is possible, in view of the freely determinable match plate division described above, to select and predetermine the sizes of the individual match plates within the molding flask format in direct corre-

spondence to the contemplated hourly mold production rate.

A further advantage of the present invention resides in the fact that the minimum size of the molding flask format may be selected, even when match plates of various types of materials, such as plaster, wood, and metal, are employed, by consideration of the maximum dimensions of any patterns to be molded on the particular molding apparatus or device. In this manner a standard molding flask format may be employed even in the case of patterns to be molded having relatively large dimensions. This is possible because changing of the corresponding match plates in the apparatus is extremely easy requiring a minimum expenditure of time. The apparatus according to the present invention, moreover, permits combination of match plates of various thicknesses as to form a single mold preparing device.

Thus it may be seen that there has been provided, in accordance with the invention, a device for preparing molds, comprising support means such as the mold table 1, a plurality of match plates having individual patterns thereon and mounted either on said support means or on intermediate means removably secured to said support means, and releasable means including the frame 16 and ledges 17 adapted to be connected to said support means and having a portion engageable with rim portions of the upper surface of at least some of said match plates, whereby said match plates are fixedly retained on said support means upon connection of said releasable means between said support means and said match plates.

Various changes and modifications may be made without departing from the spirit and scope of the present invention and it is intended that such obvious changes and modifications be embraced by the annexed claims.

Having thus described the invention, what is claimed as new and desired to be secured by Letters Patent, is:

1. A foundry mold assembly comprising a mold table, mold support means arranged for attachment to said mold table and for removal therefrom, means for centering said support means on said mold table, match plate means terminating in outer edges and held by said support means, respective pattern means mounted on said match plate means and spaced from the outer edges of the latter, respectively, a mold frame encompassing at least partly said mold support means and carried by said mold table, clamping ledges located adjacent predetermined outer edges of said match plate means to divide said mold frame into compartmental sections and to position said match plate means relative to each other within said mold frame, a mold flask connectable with said mold frame for location thereabove, and interengageable means located at the periphery of said mold frame and said mold flask, respectively, for connecting same with each other and with said clamping ledges and said match plate means located intermediate said mold frame and said mold flask, whereby said match plate means and said pattern means thereon may interchangeably be assembled and disassembled within said mold frame.

2. A foundry mold assembly comprising a mold table, a plurality of match plate means terminating in outer edges and spaced from said mold table, to thereby level all said plate means, respective pattern means mounted on said match plate means and spaced from the outer edges of the latter, respectively, a mold frame encompassing said match plate means and supported by said mold table, clamping edges located adjacent predetermined outer edges of said match plate means to position said match plate means relative to each other within said mold frame, a mold flask connectable with and for location above said mold frame, and interengageable means located at the periphery of said mold frame and of said mold flask, respectively, for connecting same with each other and with said clamping ledges and said match plate means located intermediate said mold frame

and said mold flask; whereby said match plate means with said pattern means thereon may be interchangeably assembled and disassembled within said mold frame.

3. A device for producing foundry molds, comprising a mold table; a plurality of sectional match plates mounted on said mold table, each of said match plates having at least one pattern on one side thereof surrounded by rim portions, and releasable means adapted for connection with said sectional match plates and said mold table, said releasable means encompassing said sectional match plates and being engageable from above with said rim portions, whereby said match plates are rigidly secured on said mold table upon connection of said releasable means between said mold table and said rim portions, said match plates being singly removable from said mold table for replacement with another match plate with pattern upon removal of said releasable means from said mold table.
